UNITED STATES PATENT OFFICE.

JACOB N. STRICKLAN, OF SAVANNAH, GEORGIA.

LOCK.

1,310,307.

Specification of Letters Patent. Patented July 15, 1919.

Application filed February 2, 1918. Serial No. 215,115.

To all whom it may concern:

Be it known that I, JACOB N. STRICKLAN, a citizen of the United States, residing at Savannah, in the county of Chatham and State of Georgia, have invented new and useful Improvements in Locks, of which the following is a specification.

This invention relates to locks, and one object is to provide a guard member mounted in position to be thrown across the key-hole upon the operation of a knob or the like on the inner side of the door, in order to prevent the insertion of a key from the outside.

15 A further object is to provide a lock in which the latch bolt is retained against movement by a tumbler thrown into operative position by a knob on the inside of the door at the same time the guard member 20 is thrown across the key slot.

A still further object is to provide in connection with the construction above named a tumbler mounted to be thrown into position for engaging the latch bolt, by a key 25 inserted from the outside of the door.

With the foregoing and other objects in view, the invention consists in the novel construction, combination and arrangement of elements hereinafter described and claimed.

30 In the drawings,

Figure 1 is a view of the lock in side elevation

Figs. 2 and 3 are side elevations, with the cover plate detached

35 Figs. 4 and 5 are fragmentary side elevations

Figs. 6 to 8 are elevations of the key-controlled elements

Fig. 9 is a detail showing the key-hole 40 guard and a rotatable device accessible from the inner side of the door

Fig. 10 is a detail showing the arrangement of the slots in one of the plates of the casing.

45 The main casing of the lock is designated 10 and is closed on one side by means of a plate 11 provided with an aperture 12 for the latch rollback, an aperture 13 accommodating the end of a tumbler throwing member, a key slot 14 and an aperture 15 for the insertion of a screw 16 for securing the plate member 11 into position.

The oppositely located plate member of the casing is provided with apertures or 55 openings corresponding with those designated 12, 13 and 14.

The latch bolt is shown at 17 and is provided with a reduced portion 18, a slot 19 extending longitudinally and a recess portion in one side thereof the end walls of 60 which are shown at 20 and 21.

The latch rollback is designated 24 and the projecting portions 25 thereof engage the wall 21 of the bolt. The knob spindle is 65 designated 26.

A pivotally mounted tumbler shown at 28 is retained in position by means of a pin 29 constituting its pivotal point, this tumbler being provided with a slot 30 through which a pin 31 extends freely, these pins 29 and 31 70 being mounted in one side wall of the casing. An offset portion 33 is provided with a notch 34 receiving one end of a flat spring 35 which is bowed against one wall of the casing at 36, the opposite end of the spring 75 engaging an upstanding lug 38 on tumbler 28. The lower end of tumbler 28 projects laterally as shown at 39 and is provided with a curved edge co-operating with one of the slots of the key.

A bolt 40 is operated by the key when inserted from either side of the lock and the upper end 41 thereof is thrown into position for retaining the latch bolt against retraction. This bolt is provided with a slot 42 85 through which pin 29 passes, and with a slot 43 through which pin 31 passes. A laterally offset portion 44 is notched or cut away at 45, this portion being engaged by the key. A notch 46 accommodates the lug 38 projecting from the side of tumbler 28. The lateral movement of tumbler 28 about its pivot 29 throws the lug 38 out of engagement with the notch 46.

A bolt 50 is provided with a slot 51 accommodating pin 29 and with a slot 52 through which pin 31 passes. This plate has an offset 53 provided with a notch 54 engaged by the bolt throw 55 comprising a main portion or sleeve and laterally extending ears 56 and 57, the former engaging the notch 54 and the latter being engaged by the end 58 of a substantially V-shaped spring 60 passing around a pin 61 and extending upwardly into position for engaging the latch 105 at the point 62. The bolt 50 moves into the path of the latch bolt upon the movement of a key hole guard to operative position, this movement being effected by the means described below.

Rigidly mounted with reference to the bolt throw is a key-hole guard designated 65

and provided with a guard member proper shown at 66. The bolt throw 55 is provided with transverse notches 67 on opposite ends thereof in order to permit of the operation 5 of the device by suitable means applied on either side of the lock casing. The element 65 may have a laterally extending ear or ears 68 one of which is engaged by the flat spring 60.

- 10 A pin 70 passes through the bolt throw and has threaded engagement therewith, the end of the pin on the inner side of the door having a notch permitting the turning of the pin by a screw driver. The notches 67 of
- 15 the bolt throw are engaged by lugs 73 carried by sleeve 74, this sleeve being provided with a longitudinal lug 75 engaging a slot 76, in an outer sleeve 77 on which the operating knob 78 is mounted. This outer sleeve
- 20 77 is provided with lugs 79 engaging slots 80 formed in the wall members of the casing, each wall being thus provided in order to permit of the reversal of the operating device. A coiled spring 81 bears against the
- 25 end of the sleeve 77 or the adjacent surface of the knob 78 and produces engagement between said sleeve and the casing proper retaining the bolt 50 and the key-hole guard 65

in operative position. The longitudinal movement of the sleeve 77 and the subsequent rotary movement thereof operates to throw the bolt 50 and the key-hole guard to either operative or inoperative position. 30

An adjustably mounted ward is shown adjacent to the key-hole and may be positioned 35 to suit the key to be used. This ward 90 is retained in position by means of a plate member 91 through which a screw 92 passes for engaging the ward, other screws 93 retaining the plate in position. The ward is 40 provided with an offset 95 operating within a slot 96 in one of the side members of the casing.

What is claimed is:

In a device of the class described, a latch 45 bolt, a latch rollback, a key operated bolt, a tumbler coöperating with and locking the key operated bolt, a key hole guard, a bolt throw rigidly mounting the guard, a bolt projected by the bolt throw into the path of 50 the latch bolt when the key hole guard is moved to operative position, and means for operating the bolt throw.

In testimony whereof I affix my signature.

JACOB N. STRICKLAN
